His Attorney.

UNITED STATES PATENT OFFICE.

JOHN FLAMMANG, OF ST. LOUIS, MISSOURI, ASSIGNOR TO OTTMAR G. STARK, OF ST. LOUIS, MISSOURI.

PISTON.

1,236,088.

Specification of Letters Patent. Patented Aug. 10, 1920.

Application filed May 23, 1918. Serial No. 236,192.

Specification of Letters Patent.
It is known that I, JOHN FLAMMANG, a citizen of the United States, residing at St. Louis, Missouri, have invented a new and useful Piston, of which the following is a specification.

This invention relates to pistons.

The object of the invention is to provide a novel form of piston which will function properly and with a high degree of efficiency without the use of piston rings or any other kind of packing and which, because of qualities given to the piston in the course of its manufacture, presses closely against the cylinder wall and prevents closely the escape or passage of the gas, steam or other piston operating agent and at the same time conforms to all requirements of efficiency.

Another object is to provide a piston composed of a split casting expanded and set in its changed shape by a change in its molecular construction so that when placed within the cylinder for which it is intended, the piston will maintain close pressure against the cylinder wall throughout its circumference and thus make unnecessary the use of piston rings or packing of any kind.

The general object of the invention is to provide an improved piston composed of a split casting possessing the qualities and characteristics hereinafter described.

Various other objects and advantages will be apparent from the following description in the course of which reference is made to the accompanying drawings, illustrating the piston in several stages of its construction from the rough casting to the finished piston, and in which—

Figure 1 is a view partly in section illustrating a form of casting which may be used satisfactorily in the construction of a piston in accordance with my present invention.

Fig. 2 is a view illustrating the same casting after several stages of treatment.

Fig. 3 is a view of the casting after the metal has been expanded and placed under tension, the molecular arrangement having been changed to set the material in expanded shape.

Fig. 4 is a view partly in section after the wrist pin has been applied to the piston casting, the metal above the wrist pin being held under tension ready for the casting to

be finished as to its circumferential surface.

Fig. 5 is a view of the casting held under tension within a cylinder, in which the treatment of the body of the piston is finished and made ready for the head plate to be applied.

Fig. 6 is in elevation of the finished piston.

Fig. 7 is a sectional view of the piston mounted within a cylinder.

In the particular form of the invention illustrated the piston body is composed of a lower ring 1, an upper ring 2 and a pair of diametrically opposite connections 3 by 70 which the upper and lower rings are integrally united. The connections 3 are formed with inwardly extending bosses 4 through which the holes for the wrist pins are formed, as will presently appear, and two alined arms 5 extend inwardly from diametrically opposite sides of the ring 2 above the bosses 4. Each of the arms 5 is formed with an upward extension 6 at its inner end, said extensions being a suitable 80 distance apart so that when it is desired to compress or tension the upper portion of the cylinder there will be sufficient room for movement of the extensions 6 toward each other.

The casting is then preferably tapered slightly as illustrated in Fig. 2, in which the dotted lines 7 illustrate the original dimensions of the casting, though this operation may be dispensed with if desired. The upper ring 2 of the casting is then cut on diametrically opposite sides as shown at 8. While the cuts 8 as shown are vertical it is apparent that they may be inclined or formed otherwise at the option of the manufacturer or user.

After the ring has been cut in the manner described the connections 3 are placed under tension. As shown (Fig. 3) this is accomplished by forcing a wedge or block 9, or any proper implement, between the bosses 4 in order to spread apart the upper portion of the casting. While the casting is held under tension the casting is subjected to heat or otherwise treated, as, for instance, by 100 hammering, in order to change the molecular arrangement of the metal and set the material in its expanded shape. After the metal has been treated and has been set in its expanded shape the alined holes 10 for 110

the wrist pin are formed through the connections 3 and the bosses 4, and the wrist pin 11 is forced into the holes thus provided. The wrist pin may be held within the holes 5 in which it is placed by set screws 12.

After the wrist pin has been placed in position the two separate parts of the upper ring 2 are forced toward each other in order to bend inwardly and mechanically tension 0 the connections 3 above the wrist pin. This may be accomplished in any desired manner, as by passing a bolt 13 through holes in the extensions 6 of the arms 5 and turning the nut on the bolt until the proper tension is 15 effected. While the casting is thus retained under tension the periphery of the casting is ground or turned and finished to the diameter of the cylinder for which it is intended, it being understood that the lower ring 1 20 and the connections 3 to points just above the wrist pin are finished to a diameter slightly less than the diameter of the cylinder for which the piston is intended. This is to prevent the comparatively unyielding 25 portion of the piston from becoming caught in the cylinder when in operation. Thus, when the piston is placed in the cylinder after being finished, pressure will be imparted against the cylinder wall all around, 30 due to the fact that when the open ring 2 was finished to the diameter of the cylinder it was held under tension; and when released from tension the resiliency of the metal will cause the ring 2 to exert the required pressure 35 against the wall of the cylinder.

After the periphery of the piston has been finished while the material is held under tension as described, the piston is placed within a cylinder 14 (Fig. 5) of the same 40 diameter as the diameter of the cylinder for which the piston is intended. The piston is thereby held under compression or tension after the bolt 13 is removed. The upper excess portion of the ring 2 is then removed, 45 said ring being cut at right angles to its axis below the arms 5 and in the embodiment illustrated an internal groove 15 is formed in the ring 2. Also, either before the piston is placed in the cylinder 14 or after removal 50 therefrom, as desired, a number of circumferential grooves 16 are formed in the ring 2 for the purpose of receiving oil or lubricant whereby the necessary lubricant is applied between the piston and the cylinder 55 in which it operates.

The top or head plate 11 of the piston is seated upon the ring 2 and is formed with a cylindrical portion 18 extending into the ring 2. The cylindrical portion 18 is formed 60 with a circumferential flange 19 engaging within the groove 15 and thus locking the top or head plate in connection with the body of the piston. The use of the locking flange 19 is optional, however, and any other 65 appropriate form of device may be employed

to hold the top plate in connection with the body of the piston and one such form of device is illustrated.

The spaces between the ends of the separated parts of the ring 2 are closed as to 70 passage of gas or other piston operating agent by keys 20 seated in grooves formed in the ends of the ring sectors and in the top or head plate of the piston. Thus the keys 20 in addition to preventing the passage of gas between the ends of the ring sections, also lock or hold the top plate in connection with the body of the piston leaving it optional as to whether or not the retaining flange 19 is employed. The keys are 75 held in position by the cylinder wall and in no way interfere with the freedom of expansion and compression of the piston. The diameter and circumference of the top or head plate 17 are very nearly the same 80 as the internal diameter and circumference of the cylinder for which the piston is intended, so that when the upper ring of the body of the piston is compressed and placed within the cylinder, the diameter of the top head plate and the diameter of the upper ring of the piston body are very nearly the same. Before the piston is compressed within the cylinder the upper open ring 2 is of 85 larger diameter in the plane of the axis of the wrist pin than the diameter of the top or head plate, as will be understood by reference to Fig. 6.

The upper edge of the ring 1 is beveled to provide a scraping edge 21 which during 90 downward movement of the piston will scrape the oil from the cylinder wall; and the lower edge of the ring 2 is beveled to provide a scraping edge 22 which during 95 downward movement of the piston will 100 scrape the oil from the cylinder wall.

From the foregoing description it will be understood that by my present invention the upper portion of the piston body is mechanically placed under tension and then 105 the molecular structure is changed to set the metal in its changed shape, and that the lower portions of the connections 3 are held in their expanded shape by the wrist pin when the upper portion of the 110 piston is compressed by application thereto of the bolt 13, or otherwise. The resiliency of the metal of the piston constructed in this manner permits free expansion and contraction so that the piston is at all times in 115 conformity with the cylinder.

What I claim and desire to secure by Letters Patent, is:—

1. A piston composed of a body expanded from its upper end to a point below the 125 wrist pin and set in its expanded shape, and a wrist pin preventing compression of that portion of the piston below the wrist pin.

2. A piston composed of a split body expanded from its upper end to a point below 130

- the wrist pin and set in its expanded shape, said upper portion being expansible and compressible whereby the resiliency of the metal will press the upper portion of the 5 piston body against the wall of the cylinder in which the piston is mounted; and a wrist pin mounted in the expanded portion of the piston.
3. A piston composed of a tapering body 10 whose upper portion is expanded and set in its expanded shape, said upper portion being expansible and compressible, whereby the resiliency of the metal will press the upper portion of the piston body against the wall of the cylinder in which the piston is mounted; and a wrist pin mounted in the expanded portion of the piston and permitting expansion and compression of the piston above the wrist pin and preventing 15 compression of the piston body below the wrist pin.
4. A piston comprising a body whose upper portion is of a diameter in excess of the diameter of the cylinder for which the 20 piston is intended, and which is compressible into the cylinder whereby the material of the piston is placed under tension; a wrist pin permitting expansion and compression of the piston above the wrist pin and preventing compression of the piston 25 below the wrist pin; and a top plate in connection with the body of the piston.
5. A piston comprising a body whose upper portion is mechanically expanded, and 30 which is then set in its expanded shape; and a wrist pin attached in the piston body, the upper portion of the piston body being compressed under tension and finished to a size equal to the internal size of the cylinder for 35 which the piston is intended while the piston is compressed.
6. A piston comprising a body composed of a lower ring, an open upper ring, and 40 connections integrally uniting the upper and lower rings, the upper ring being expanded to a size in excess of the diameter of the cylinder for which the piston is intended and set in its expanded shape; a top plate 45 for the piston; interlocking releasable connection between the piston body and the top plate; and a wrist pin mounted in the piston after it has been expanded.
7. A piston comprising a body composed of an integral lower ring, an open upper 50
- ring, and connections integrally uniting the 55 upper and lower rings; the upper ring being expanded to a size in excess of the size of the cylinder for which it is intended and set in its expanded shape; a wrist pin secured to said connections; and a top plate 60 connected to the upper ring and being of approximately the same diameter as the diameter of the cylinder for which the piston is intended.
8. A piston comprising a body composed of a lower ring, a split upper ring expanded to a size in excess of the size of the cylinder for which it is intended, and being set by treatment in its expanded shape; connections integrally uniting the lower and upper 65 rings; a wrist pin mounted in said connections; a top plate secured to the upper ring; and a device closing the space between the ends of the upper ring.
9. A piston comprising a body composed of a lower ring, a split upper ring expanded to a size in excess of the size of the cylinder for which the ring is intended, and being set in the expanded shape; connections integrally uniting the lower and upper rings; a 70 wrist pin rigid with said connections and limiting resilient action thereof; a top plate in connection with the upper ring; and keys holding the top plate in connection with the upper ring and closing the space between 75 the ends of the upper ring.
10. A piston comprising a body, having a split upper portion, said upper portion having a radius of curvature greater than the radius of curvature of the cylinder for 80 which the piston is intended, a top plate seated upon the split upper portion of the piston, and a wrist pin supported by the piston body.
11. A piston composed of a split body, 85 a portion of which above the wrist pin is of a diameter greater than the diameter of the cylinder for which the piston is intended, said portion being expansible and compressible, whereby the resiliency of the metal 90 will press said portion against the wall of the cylinder in which the piston is mounted; a wrist pin supported by the piston body; a top plate supported by the piston body; and means releasably holding the top plate 95 in connection with the piston body.

JOHN FLAMMANG.
